UNITED STATES PATENT OFFICE

111,190

DESIGN FOR A CHECK IMPRINTING MACHINE OR SIMILAR ARTICLE

Walter B. Payne and Richard C. Browne, Rochester, N. Y., assignors to The Todd Company, Inc., Rochester, N. Y., a corporation of New York

Application June 25, 1938, Serial No. 78,081

Term of patent 14 years

To whom it may concern:

Be it known that we, Walter B. Payne and Richard C. Browne, both citizens of the United States and residents of Rochester, in the county of Monroe and State of New York, have invented a new, original, and ornamental Design for a Check Imprinting Machine or Similar Article, of which the following is a specification, reference being had to the accompanying drawings, forming a part thereof.

Fig. 1 of the drawings is a perspective view of a check imprinting machine or similar article,

embodying our design, the essential features of the design being shown in full lines.

Fig. 2 is a similar view of the same, looking at it obliquely from the opposite side, and

Fig. 3 is a rear elevation of the machine.

We claim:

The ornamental design for a check imprinting machine or similar article, substantially as shown and described.

WALTER B. PAYNE.
RICHARD C. BROWNE.
